UNITED STATES PATENT OFFICE.

EMIL BOMMER, OF BROOKLYN, NEW YORK.

SPRING HINGE.

Application filed March 5, 1925. Serial No. 13,013.

This invention relates to spring hinges and has for its object to provide an improved spring hinge which may be readily moved and is very simple in its constituent parts and also has for its object to provide a very simple and desirable method and structure permitting the alignment of the door to its support.

More particularly an improved feature of my spring hinge is to provide the cylindrical pivotal shaft with swaged extensions against which the shoulders of the spring end gauging plates abut and, furthermore, particularly the improvement consists in providing a cylindrical extension to the pivotal shaft and disposing between a shoulder of this extension and a supporting member a knurled collar, the knurled surface of which engages the surface of the shoulder and the surface of the support when the shoulders are fastened together in such a way as to bring about a firm alignment of the parts.

The invention will be more fully described hereinafter. Embodiments thereof will be shown in the drawings and the features of the invention finally pointed out in the claim.

In the accompanying drawings,—

Figure 1 is a vertical section through the casing of my improved spring hinge embodying the features of the invention forming the basis of this present application;

Fig. 2 is a horizontal section taken on line 2—2 of Fig. 1;

Fig. 3 is a plan view of the knurled collar;

Fig. 4 is a perspective view of the plate having a shoulder;

Fig. 5 is a perspective view of my improved pivot shaft having swaged extensions; and

Fig. 6 is a section taken on line 6—6 of Fig. 5.

Similar characters of reference indicate corresponding parts throughout the various views.

Referring to the drawings and more particularly to Fig. 1, the door jamb or support is indicated generally by 10, and the door itself by 11. To the door is fastened bracket 12 of my improved spring hinge by suitable screws 13 and the door has a recess 14, into which a projection 15 of the casing fits. The casing at the lower portion is provided with an opening 17 formed by flange 16 of a cap portion 18 suitably held in place by screws 19. The casing is substantially cylindrical and is indicated by 20. Within the casing a central pivot pin 21 having an upper end 22

seated within the socket 15 is arranged. The lower end of the pivot pin 21 is provided with a portion 22^a fitted within the inner surface flange 16. This portion 22^a forms a shoulder 23 in respect to a portion 24 of smaller diameter and the lower end of the portion 24 is cylindrical and provided with exterior screw threads 25. Disposed on the pivot pin 21 in the portion thereof within the cylindrical casing 20 is an upper plate 26 and a lower plate 27, said plates being preferably of malleable cast iron. These plates have extending portions 28, each plate having a bore conforming to the exterior diameter of the pin 21 and each having a shoulder portion 29. A helical spring 30 has one end 31 bent inwardly and engaging within a recess 32 in the plate 26 and the other end of the spring is bent inwardly and engages within a corresponding recess in the plate 27. The interior of the casing is provided with a rib 34 against which projecting shoulders 33 of the plates 26 and 27 abut.

The pin 21 is made of certain construction which is believed to be novel in the art and consists essentially of having two projections 34 and 35 swaged out of the material composing the pin when the pin is in its original cylindrical form. These projections 34 and 35 are abutted by the shoulders 29 of the plates 26 and 27 and are yieldingly maintained in engagement with the shoulders 29 by the torsional action of spring 30 which is placed under considerable tension in placing the plates in the position shown. The pin itself is made of a single piece of cold drawn steel finished in an automatic screw machine and the shoulders 34 and 35 are automatically swaged outwardly in a press operation, being shaped out of the curved portion formed within the contour of the pin, as shown in Fig. 6.

The cylindrical portion 24 of the pivot pin fits into a bore 37 of a support 38 on a suitable bracket 39 adapted to be secured to the door support or jamb. Interposed between this member 38 and the shoulder 23 is an annular collar having a bore of the diameter substantially equal to the diameter of the cylindrical portion 24 and this annular collar indicated by 40 has its upper and lower surface provided with knurled portions, as indicated by 42 in Fig. 3. When it is desired to align the door, the nut 44 is loosened and the pin may be readily rotated in respect to the support 38 until the position of the door in

respect to the jamb is obtained. When the desired position has been decided upon the nut 44 is screwed along the screw threaded portion 25 and thereby the shoulder 23 is forced against the knurled portion 42 of the annular collar 40 and at the same time the other surface having the knurled portion of the annular collar is forced against a seat 46 of the support 38. By this engagement 10 the knurled surface of the collar 40 with the shoulder 23 and the support 38 are very securely held and a tight wedging action is obtained which is of such a character that when the nut 44 has been screwed tight then the 15 door is aligned and the parts properly held in position.

In the accompanying drawings and foregoing description, I have disclosed a particular embodiment of the invention which has proven highly satisfactory. The parts are of simple construction and in their cooperation a spring hinge for double swinging doors which is light, strong and durable is provided. It will be apparent that the improved spring 25 hinge construction is susceptible of modifica-

tion. Accordingly, the privilege is reserved of resorting to all such legitimate changes in form, proportion and arrangement of the several cooperating parts as may be fairly embodied within the spirit and scope of the invention as claimed. 30

What is claimed as the invention and is desired to be secured by Letters Patent is:

A spring hinge comprising an apertured bracket, a pivot pin seated in the aperture in the bracket, means for locking the pin in fixed position in the bracket, the pivot pin being substantially cylindrical and having vertically extending shoulder means between the upper and lower ends thereof, said shoulder means being swaged out of the cylindrical stock forming the body of the pivot pin, a spiral spring surrounding the pivot pin, and upper and lower collars carried on the pivot pin, each engageable with an end of the 40 spring, and with said swaged-out shoulder means. 45

In testimony that I claim the foregoing as my invention, I have signed my name hereto.

EMIL BOMMER.
